UNITED STATES PATENT OFFICE.

DANIEL PALMER BANFILL, OF RICHMOND, MICHIGAN.

MUSIC-LEAF TURNER.

No. 896,609.

Specification of Letters Patent.

Patented Aug. 18, 1908.

Application filed July 23, 1907. Serial No. 385,192.

To all whom it may concern:

Be it known that I, DANIEL PALMER BANFILL, a citizen of the United States, residing at Richmond, in the county of Macomb and State of Michigan, have invented new and useful Improvements in Music-Leaf Turners, of which the following is a specification.

This invention is an improved music leaf turner adapted for use in connection with a piano or other like musical instrument to enable the performer to turn the leaves of the music without having to employ his hands for such purpose.

The said invention consists in the construction, combination and arrangement of devices hereinafter described and claimed.

In the accompanying drawings, Figure 1 is a perspective view of a music leaf turner embodying my invention, showing the same arranged in operative position and employed in connection with the piano. Fig. 2 is a detail top plan view of a portion of my improved music leaf turner. Fig. 3 is a detail sectional view of the same. Fig. 4 is a detail sectional view showing a portion of the tubular frame and the foot actuated devices mounted in the lower portion thereof. Fig. 5 is a detail perspective view showing one of the members of my improved music leaf turner. Fig. 6 is a detail longitudinal sectional view of the back or base of the music leaf turner. Fig. 7 is a detail sectional view of the same taken on the plane indicated by the line *a—a* of Fig. 6. Fig. 8 is a detail perspective view partially in section.

In the embodiment of my invention here shown, a base or back board 1 is provided of a suitable size to hold a piece of music when the same is open and is adapted to be placed on the rack of a piano or other musical instrument and to be supported in an upright position on such rack. Such back or base board is provided with longitudinal guide slots or grooves 2 in its face which extend to its opposite ends and are provided with undercut walls which engage similarly shaped edges or plates 3 which are slidable longitudinally in such grooves and are provided on their outer sides with spring clamping arms 4 which coact with such plates to form clamps for engaging the outer edges of the backs, covers, or outside leaves of a music book or piece of music so as to hold such back or piece of music in an open position on such base or back board 1. Such clamps being slidable

longitudinally in the grooves 2 are adjustable to accommodate them to music books, sheets or pieces of various sizes.

A frame 5 which is rectangular in form is also provided. The said frame is of such size as to enable it to be fitted on the front of the piano or like instrument, as shown in Fig. 1. The upper side of said frame is secured to the lower side of the back or base board 1, the latter being midway between the ends of said frame. The bottom, top and ends of the frame are tubular, as shown in detail in Fig. 4. The tubular bottom bar of the frame is provided at a suitable distance from one end, preferably its left end, with a casing 6 which rises from its upper side and in which is secured a non-revolvable horizontally disposed axle 7 on which is mounted a number of foot actuated revoluble devices 8, 9, 10 and 11, which are here shown as wheels or disks, each provided on its upper peripheral surface with a roughened tread portion 12. On one side of each of the said foot operated devices is a gear segment 13 engaged by a pinion 14 on a vertically disposed drum shaft 15, said shafts having their bearings at their upper and lower ends, respectively, in openings in the top of the casing 6 and in the bottom of the tubular bottom bar of the frame. In the corners of the said tubular frame are direction sheaves or pulleys 16.

On the center portion of the back or base board 1 are mounted a plurality of shafts 17, 18, 19 and 20 which are tubular and are nested one within another and are respectively provided at their lower ends with pulleys 21, 22, 23 and 24. Any desired number of such shafts may be provided and the same is also true as to the foot operated devices hereinbefore described, one of such foot operated devices being employed in connection with each of such shafts. Any suitable number of operating cords are also provided, said cords being endless, passed around the sides of the frame within the tubes forming such frame, engaging the direction elements 16 and each being partly wound on one of the drum shafts and partly wound on the pulley of one of the tubular shafts so that when any one of the foot operated devices is partially turned, rotary motion will be imparted to the drum shaft geared thereto and such drum shaft will cause the cord connected thereto to be pulled in one direction or the other, such cord by en-

agement with the pulley on the tubular shaft serving to turn such tubular shaft in one direction or the other, as will be understood. The said cords are for the purposes of this specification respectively indicated at 25, 5 26, 27 and 28. An arm 29 is attached to and carried by each of such tubular shafts. Such arms each constitute a frame having an inner member 30 connected to such tubular shaft 10 by bars 31 and an outer frame 32 having tubular portions which receive the upper and lower arms of the inner frame, so that such outer frame is adjustable longitudinally with respect to the inner frame to accommodate 15 itself to the size of the leaves of the piece of music. Each of the said arms has its outer frame or member provided with a clamp 33 to engage the outer edge of the music leaf and secure the same thereto. The tubular shafts are provided with openings 34 in one side thereof to clear the bars 31 of the other shafts so that each of the said tubular shafts 20 with its leaf turning bar is adapted to be turned independently of the other shafts.

25 The performer by placing his foot on the foot operated devices and moving the same in the required direction may cause the leaves of the piece of music to be turned in succession from time to time as required, thus leaving his hands free to operate upon 30 the keys of the instrument.

To keep the back of the music book or sheet from coming in contact with the outer tubular shaft 20, is provided fenders 35 which are secured on the front side of the base or back board 1 and extend across such outer tubular shaft.

I do not desire to limit myself with the exact construction, and combination of 40 devices herein shown and described, as it will be seen that modifications may be made

therein within the scope of the appended claims.

Having thus described the invention, what I claim as new and desire to secure by Letters 45 Patent is:—

1. A music leaf turner, comprising a base, a plurality of shafts mounted thereon and disposed one within another, each of said shafts having a leaf-engaging arm and provided with a pulley, endless cords respectively engaged and partly wound on such pulleys, direction elements for such cords, foot operated devices, drum shafts on which such cords are respectively partially wound 50 and gearings connecting each of such drum shafts with one of said foot operated devices, substantially as described.

2. A music leaf turner comprising in combination with a leaf turning device having a pulley, a frame on which such leaf turning device is mounted, said frame having tubular portions, operating cords for the leaf turning devices mounted in such tubular portions of the frame, foot operated devices 60 mounted on such frame and drum shafts for the respective cords geared to such foot operated devices.

3. In a music leaf turner, a plurality of tubular shafts disposed one within another 70 and each having means whereby it may be turned, and further provided with a leaf engaging member and a slot or opening in one side to clear the leaf engaging members of the other tubular shafts.

In testimony whereof, I affix my signature 75 in presence of two witnesses.

DANIEL PALMER BANFILL.
